(57) **CLAIM**

The ornamental design for blood pressure monitor, as shown and described.

DESCRIPTION

1. Blood pressure monitor
1.1 is a perspective view showing the blood pressure monitor of my design;
1.2 is a front elevational view thereof;
1.3 is a rear elevational view thereof;
1.4 is a left side elevational view thereof;
1.5 is a right side elevational view thereof;
1.6 is a top plan view thereof; and
1.7 is a bottom plan view thereof.

The broken lines depicting portions of the blood pressure monitor shown in the drawings form no part of the claimed design.
